UNITED STATES PATENT OFFICE

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA

HEAT-TREATING APPARATUS FOR CANNED GOODS

Application filed April 18, 1928, Serial No. 271,068. Renewed December 5, 1930.

This invention relates to a treating apparatus for canned goods and is more particularly related to an apparatus for use in the heat treating of canned goods, the apparatus being capable of control to enable the operator to vary the "time of cook" throughout the entire apparatus as desired.

In the canning art, different types of canned goods require different treatments and require different "times of cook." After the goods have been hermetically sealed within the cans, the cans are subjected to what is known as the final cook, and it is common practice to pass the cans through large heating chambers in order to effect this final cook. The requirements of the canning industry have made it necessary to construct this cooking apparatus to provide extremely large chambers having enormous can capacities and in order to effect the different required times of cook it has been the common practice to vary the speed with which the cans are forced through the chambers. The tendency in the art is to increase the size of these cookers and it has been found that within practical limits the maximum size which these cookers can be built has been approximately reached. The cookers, or heating chambers, which are now commonly used include a shell having formed on its inner periphery a helical track through which the cans are caused to travel by means of a reel secured to a shaft which extends longitudinally of the shell. A mechanical limit is therefore obviously present, beyond which the size of these heating chambers can not be practically increased. As the span from end to end of these chambers increases, the tendency of the driving reels to sag intermediate the ends becomes markedly increased. The greater the required speed of operation of this type of heat treating apparatus, the smaller it is necessary to make the apparatus, as in the driving reels the apparatus are driven at accelerated rates the tendency of the reels to sag becomes greater.

It is therefore an object of this invention to provide a heat treating apparatus for canned goods which includes a multiplicity

of successive chambers through which the canned goods are caused to pass, the successive chambers having a multiplicity of inlets or outlets through which the cans may be admitted to, or discharged from, the cookers in order to vary the "time of cook" of the canned goods passing through the apparatus.

Another object of this invention is to provide a variable heat treating apparatus which includes a plurality of separate successive treating chambers, one of the chambers being provided with more than two independent openings providing inlet and outlet means from said chamber, the other of said chambers being provided with an inlet and an outlet means for introducing said cans into one of said openings and means for discharging cans from another of said openings and means for bypassing one of said chambers.

Other objects and advantages of this invention it is believed will be apparent from the following detailed description of a preferred embodiment thereof as illustrated in the accompanying drawings:

In the drawings:

Figure 1 is the diagrammatic top plan view of a heat treating apparatus embodying this invention.

Figure 2 is a top plan view of a modified form of heat treating apparatus embodying this invention.

In the embodiment of this invention illustrated in Figure 1, 1 indicates what is termed in the canning art as a "cooker" and 2 indicates a second cooker. What is known in the art as a "cooler" is indicated at 3. The cookers 1 and 2, and cooler 3 may be of any suitable or desirable form of construction, as is well understood in the art, one form of which includes a shell within which a track (not shown) is formed through which the hermetically sealed food products are caused to pass by means of reels (not shown) secured to the shafts 4, 5 and 6. The shafts 4, 5 and 6 are coupled together by means of couplings, 7 and 8, which may be of any suitable or desirable construction as is common in the art. Any suitable or desirable means (not

shown) may be provided for heating the canned goods within the cookers 1 and 2, such, for example, as admitting live steam into the shells of the cookers 1 and 2, and any suitable or desirable means may be provided for cooling the canned goods in the cooler 3 as, for example, admitting cold air or other gases under pressure into the shell of the cooler 3.

10 Means are provided for transferring the cans from the cooker 1 to the cooker 2 such, for example, as is diagrammatically illustrated at 9. Means are likewise provided for transferring the cans from the cooker 2 to the cooler 3, as is diagrammatically illustrated at 10. The transfer means 9 and 10 may be of any suitable or desirable construction, but are preferably of the form illustrated in my copending application filed 15 April 18, 1928, Serial No. 271,070. The shell of the cooker 1 is provided with a multiplicity of openings, 11, 12, 13, 14, 15 and 16, through which the cans to be heated may be admitted into the cooker 1, depending upon 20 the time of cook desired. The cans may be admitted into any one of said openings, 11, 12, 13, 14, 15 or 16 by means of a slidably mounted trough 17 which is slidably mounted on the conveyor 18 to permit the same to be 25 moved to the desired position to cause the cans to enter the shell of the cooker 1 through any one of the openings 11, 12, 13, 14, 15 or 16. The exact construction and mode of operation of this type of mechanism is illustrated in my copending application filed 30 April 18, 1928, Serial No. 271,070.

When it is desired to subject the canned goods to a "long cook", the cans are admitted into the cooker 1 through the opening 11 and are transferred by the transfer means 9 to the cooker 2 and are then transferred by the transfer means 10 to the cooler 3. If a shorter "time of cook" is required, in order to correctly process the canned goods, the 40 canned goods may be admitted to any one of the openings 12, 13, 14, 15 or 16, and if desired the cans may be bypassed along the conveyor 18 by the cooker 2 directly to the cooler 3. It will therefore be obvious that the canned goods may be subjected to any desired "time of cook" depending upon the inlet through which the cans are admitted into the cooker 1 and on whether or not the canned goods are caused to bypass the cooker 2 or pass through the cooker 2. In order to bypass the cooker 2, the inlet trough 19 of the transfer means 9 may be pivotally supported so that the same may be swung out of operative position to cause the cans to pass 45 along the conveyor 18 rather than pass into the cooker 2. The inlet trough 19 may also be provided with a gate 20 which closes the inlet trough 19, and a gate 21 which may be lifted from position to permit the cans to 50 pass directly along the track 18.

The inlets 11, 12, 13, 14, 15 and 16 are preferably formed at equally spaced intervals along the shell of the cooker 1 so that if the cans are admitted into the cooker 1 through the inlet 11, the cooker 1 has a capacity of, for example, 1500 cans. If the cans are admitted through the inlet 13, the cooker will have a capacity of 1000 cans, and if the cans are admitted through the inlets 14, 15 or 16, the cooker will have a capacity of 750, 500 or 250 cans respectively. The cooker 2 may likewise have a capacity of 1500 cans so any "time of cook" may be had between the ranges of the capacities of 250 and 3000 cans as desired, or required, in order to correctly process the canned goods without varying the speed at which the shafts 4, 5 and 6 of the combined cooker and cooler are operated.

In the modified form of this invention illustrated in Figure 2, 1^a is combined with a cooker 2^a and with a cooler 3^a. The cooker 1^a may be provided only with an inlet 11 and an outlet 22^a. The cooker 2^a is provided with a multiplicity of outlets 23^a, 24^a, 25^a, 26^a and 27^a, and a single inlet 29^a. A third cooker 30^a may be connected in the combination and each of the cookers 1^a, 2^a and 30^a may have a capacity of 1000 cans, or such other capacity as may be desired. The track 18^a is provided with slidably mounted chutes 17^a and is arranged so that either the cookers 1^a or 30^a may be bypassed as desired, depending upon the "time of cook" required in order to correctly process the canned goods. For example, by bypassing the cooker 1^a and admitting the cans into the cooker 2^a through the opening 29^a, any desired "time of cook" may be had by taking the cans out of the cooker 2^a through any one of the openings 23^a to 27^a respectively, giving a cooker capacity of from 200 to 1000 cans, that is, by bypassing also the cooker 30^a. A capacity of 1200 cans may be had by either passing the cans through the cooker 1^a and then into the cooker 2^a through the opening 29^a and out through the outlet 23^a, or by passing the cans into the cooker 2^a through the opening 29^a and out the outlet 23^a and then into the cooker 30^a. It will be obvious that any desired "time of cook" may be had in this combination of cookers and cooler within a range of from 200 cans to 3000 cans in steps of 200 can capacities of the entire apparatus. The transfer means for transferring the cans from the cooker 1^a to the cooker 2^a and from the cooker 2^a to the cooker 30^a and from the cooker 30^a to the cooler 3^a are diagrammatically illustrated at 9^a, 10^a and 31^a respectively. The multiple outlet construction of the cooker 2^a may be of any suitable or desirable form, one form of which is particularly illustrated and described in Patent No. 1,210,563, granted January 2, 1917, to me.

Having fully described my invention, it

is to be understood that I do not wish to be limited to the details herein set forth but my invention is of the full scope of the appended claims.

5 I claim:

1. An apparatus for treating canned goods comprising a series of compartments in axial alignment having a common canway located adjacent said compartments, means for diverting cans into each of said compartments and means for delivering cans back onto the runway from any of said compartments, one of said compartments having more than two openings constituting inlets and discharge to vary the length of travel of the cans in one or more of the compartments.

2. An apparatus for treating canned goods comprising a series of treating chambers in axial alignment arranged in connected operative relation, a common canway located adjacent said compartments the canway being provided with movable switches and the compartments being provided with variable inlets and outlets whereby the movable switches may be shifted in relation to said inlets and outlets to shunt the cans to and from said common can way around a part of said compartments and a part of one of said compartments.

30 Signed at San Jose, Calif., this 29th day of February, 1928.

ALBERT R. THOMPSON.
